MECHANISM FOR WALKING TOYS

Carl Larsen, Globe, Ariz.

Application March 11, 1938, Serial No. 195,391

3 Claims. (Cl. 46—105)

This invention relates broadly to walking toys and more particularly to an improved mechanism for operating the limbs or legs of such toys.

Particularly the invention is concerned with the provision of an improved mechanism for use in connection with walking toys of the quadrupedal type and aims to provide a mechanism which will tend to give a more or less natural movement to the limbs or legs.

The invention together with its objects and advantages will be best understood from a study of the following description taken in connection with the accompanying drawings wherein—

Figure 1 is a view partly in section and partly in elevation illustrating my improved mechanism in association with a quadrupedal animal-simulating toy.

Figures 2, 3 and 4 are detail views taken substantially on the lines 2—2, 3—3 and 4—4 respectively of Figure 1.

Figure 5 is a detail sectional view taken substantially on the line 5—5 of Figure 1.

Figure 6 is a perspective view of a pawl rod.

Figure 7 is a perspective view of a spring member.

Figure 8 is a perspective view of a reciprocating bar hereinafter more fully referred to, and

Figure 9 is a perspective view of a trip member also hereinafter more fully referred to.

Referring to the drawings more in detail it will be seen that I have shown such portions of a toy as deemed necessary for a proper understanding of the invention, as for example the torso or body 5 of the toy, and the legs 6, the body 5 and legs 6 being hollow as shown.

Mounted within the body 5 of the toy is a bracket plate 7 secured within the body in any suitable manner.

At each end thereof the plate 7 is provided with two pairs of bearing lugs, the lugs of each pair being indicated by the reference numerals 8.

Journalized in each pair of lugs 8 is a rod or shaft 9 that is provided at one end with what may be termed a leg-arm 10 that is accommodated within a leg 6 of the animal while at the inner end thereof the shaft 9 is provided with what may be termed a crank arm 11 arranged within the torso or body 5.

The front and rear shafts 9 are connected in pairs through the medium of bars 12 and 13, the bar 12 connecting the arms 11 of one pair of shafts 9 and the bar 13 paralleling the bar 12 and connecting the arms 11 of a second pair of shafts 9. To receive the ends of the bars 12 and

13 arms 11 are bifurcated as shown and are equipped with pivots 14 whereby the bars are pivoted to the respective arms 11.

The plate 7 is provided on the underside thereof and extending longitudinally of the plate at the longitudinal median thereof, with a rib 15. At its opposite ends the rib 15 is provided with depending extensions 16, that in turn are provided with inwardly directed fixed pivot elements or pins 17.

A frame comprising side bars 18 and transverse end bars 19 is provided, and the end bars 19 intermediate their ends are equipped with openings as at 19' to receive the pivot pins 17 through the medium of which the aforementioned frame is pivotally suspended from the bracket plate 7.

The leg-arms 10 are suitably equipped at their lower ends as at 20 to accommodate short shafts 21 that serve as axles for rollers 22 provided for the legs 6 of the animal.

The side bars 18 of the aforementioned frame are provided adjacent the ends thereof with apertures which receive the offset hook-like ends 23 of pawl rods 24.

The pawl rods 24 are accommodated within the legs 6 of the toy and cooperate with ratchet wheels 25 provided on the hubs of the rollers 22 in response to the swinging of the frame 18 laterally to the end that when one pair of pawl rods 24 are engaged with the ratchet wheels 25 associated with the legs 6 of the toy at one side of the latter the other pair of pawl rods are raised out of engagement with the ratchet wheels associated with the legs 6 of the toy at the opposite side of the latter as clearly shown in Figure 5.

For rocking the aforementioned frame (embodiment the side bars 18 and end bars 19) first laterally in one direction and then in a reverse direction as the toy moves forwardly there is provided on one of the side bars 18 a depending plate 26 provided with a horizontal notch 27 opening through one vertical edge of the plate as shown in Figure 1.

Also extending downwardly from the rib 15 intermediate the ends of the latter is a bearing plate 28 that is disposed opposite to a bearing plate 29 depending from one side edge of the bracket plate 7. Rotatably supported between the bearing plates 28, 29 is a shaft 30 that is provided with an arm-like projection 31 having extending therefrom a finger 32 engaging in the aforementioned notch 27 of plate 26 as clearly shown in Figures 1 and 3. It will thus be seen

that as the shaft member 30 is rotated in one direction movement thereof will be transmitted to the aforementioned frame for rocking the same in one direction while when the shaft 30 is rotated in a reverse direction said frame will also be caused to swing in a direction opposite to that first mentioned.

The aforementioned shaft 30 is releasably held in the position to which rotated through the medium of a spring 33 preferably of the shape suggested in Figure 7, and this spring 33 has an upper tapered end thereof suitably anchored to the plate 7 and a lower wider end notched as at 34 to engage a suitable projection 35 provided therefor on the aforementioned shaft 30 as best shown in Figure 4.

Also for rocking the shaft 30 incidental to the travel or movement of the toy there are provided on the bar 13 a pair of relatively spaced inclined lugs 36, 37 that normally accommodate therebetween a trip lug or extension 38 also provided on the aforementioned shaft 30 and as will be clear from a study of Figures 1, 4 and 8. It will thus be seen that as the bar 13 moves in one direction lug 36 thereon will engage the member 38 to cause the shaft 30 to rock in one direction while when the bar 13 moves in a reverse direction lug 37 will engage the member 38 to rock the shaft 30 in a reverse direction; the rocking of the shaft 30 in this manner causing the aforementioned frame embodying the side bars 18 to first rock in one direction and then in a reverse direction so that in alternation one pair of legs have the rollers 22 thereof momentarily latched against rotative movement while the rollers 22 associated with the other pair of legs are unlatched and free to rotate. Thus under forward travel of the toy, the latched rollers 22 first on one side of the toy and then on the other will frictionally engage the ground and drag along the same. Frictional resistance to forward travel of the dragging rollers will cause the related legs 6 to be swung from a forward to a rearward position. By means presently described, rearward swinging of the legs on one side of the toy will cause the pair on the other side to be swung from a rearward to a forward position so that leg action is effected simulating walking.

The bars 12 and 13 are loosely connected intermediate their ends through the medium of a cross rod 39 which has the ends thereof loosely engaging in apertures provided in upstanding lugs 40 provided at the outer ends of lateral extensions or flanges 41 provided respectively on said bars 12 and 13 as shown in Figure 2. Intermediate its ends, and as shown in Figure 2, the rod 39 is provided with a block 42. Block 42 is provided with a vertical opening which accommodates a fixed pivot rod 43 that depends from the aforementioned bearing plate 28 as best shown in Figure 4.

Also to limit the swinging movement of the bars 12 and 13, one of the bars, for example the bar 13, is provided with a pair of spaced parallel lateral extensions 44 between which the lower end of the aforementioned pivot rod 43 extends. Obviously with the lower end of the pivot rod 43 extending between the lateral extensions 44 one of the extensions will strike the member 43 when the bar 13 moves in one direction to limit further movement of the bar in said direction, while when the bar 13 moves in a reverse direction the other of the extensions 44 will engage the pivot rod 43 to limit further movement of the bar 13 in this last-named direction.

Also referring to Figure 2 it will be noted that the extensions 20 on the lower ends of the leg-arms 10 are suitably slotted as at 20' in the top portions thereof to accommodate the lower portions of the pawl rods 24 so as to act as guides for 5 these pawl rods.

It will also be noted that at the lower ends thereof the pawl rods 24 are reversely bent to provide a suitable head for each pawl rod to engage its associated ratchet wheel 25. 10

While it is believed that a clear understanding of the invention may be had from the foregoing a brief description thereof may be set out as follows:

Referring now to the operation and beginning 15 with the parts in the position shown in Figure 1 wherein the legs 6 on the far side of the toy are in forward position and the rollers 22 thereof latched, under forward travel of the toy said latched rollers 22 dragging over the ground will 20 cause rearward swinging of the leg-arms 10 on the far side of the toy, together with the related legs 6 and crank arms 11. Such movement of said arms 11 moves the bar 12 rearwardly. The lug 40 of bar 12 swings its adjacent end of the 25 cross rod 39 about the relatively fixed pivot rod 43 in a direction such that the bar 13 is moved forwardly by coaction of the other end of said cross rod with the lug 40 of bar 13. This forward movement of the bar 13 swings the crank 30 arms 11 on the near side of the toy forwardly and hence the related leg-arms 10 and legs 6 on the near side of the toy, the unlatched rollers 22 on the near side being, as will be remembered, conditioned for rolling and thereby permitting free 35 forward movement of their related legs 6, leg-arms 10 and crank arms 11. At this point, it may be mentioned that the limits of forward and rearward movement of the bar 13 are established by engagement of the lugs 44, 44 with the pivot 40 rod 43, respectively, and the bar 13 being coupled to bar 12 by cross rod 39 corresponding limits of movement of the bar 12 are established as will be clear. Forward and rearward movements of the legs 6 on the near and far sides of the toy 45 are established by such limitation of movement of the bars 13 and 12. Under forward movement of the bar 13, the lug 37 engages the trip lug 38 on the shaft 30 and rocks the latter clockwise as viewed in Figure 1, also the finger 32. 50 The finger 32 through coaction with the notch 21 of plate 26 pulls the frame bar 18 on the near side of the toy downwardly, thereby causing elevation of the frame bar 18 on the far side. This action of said bars 18 unlatches the rollers 22 55 on the far side and latches those on the near side in a manner which has already been explained. Such rocking of shaft 30 swings the projection 35 past a dead center position relative to the axis of said shaft and the point of 60 attachment of the spring 33, whereby said shaft is yieldingly held by said spring against rocking in the opposite direction. The rollers 22 on the near side of the toy now being latched, whereas, those on the far side are now unlatched 65 and the legs 6 thereof in their rearward limits of movement, further forward travel of the toy will result in rearward swinging of the legs 6 on the near side together with the corresponding leg-arms 10 and crank arms 11 and also rearward 70 movement of the bar 13. Under rearward movement of bar 13, cross rod 39 is swung about pivot 43 in a direction to move the bar 12 forwardly through coaction of said rod with lug 40 of bar 12 and thus effect forward swinging of the legs 75.

6 on the far side in a manner which will now be clear. Under rearward movement of bar 13, lug 36 engages trip lug 38 and rocks shaft 30 counterclockwise, as viewed in Figure 1, thereby, through coaction of finger 32 with notch 27 of plate 26 elevating the frame bar 18 on the near side of the toy and lowering bar 18 on the far side. Such action of the frame bars 18, as we have already seen, latches the rollers 22 10 on the far side and unlatches those on the near side. In the counterclockwise rocking of shaft 30, the projection 35 is rocked past a dead center position relative to the axis of the shaft 30 and the point of attachment of the spring 33 to be 15 yieldingly held by said spring against reverse movement. As will now be understood, the rollers 22 are latched in the forward limits of movement of the legs 6 and unlatched in the rearward limits of movement of said legs. Further pull 20 on the toy forwardly will result in repetition of the operations set forth so that the legs 6 of the toy simulate walking.

Having thus described the invention what is claimed as new is:

- 25 1. In a quadrupedal toy, the combination of a torso and front and rear legs, a bracket plate mounted within said torso, pairs of shafts rockably supported on said plate, there being one shaft for each leg, and each shaft having a leg- 30 arm extending into a leg of the toy and a crank arm within the torso, reciprocating bar connecting the crank arms in pairs, whereby the legs at each side of the toy will swing in unison.
2. In a quadrupedal toy, the combination of 35 a torso and front and rear legs, a bracket plate mounted within said torso, pairs of shafts rockably supported on said plate, there being one shaft for each leg, and each shaft having a leg- 40 arm extending into a leg of the toy and a crank arm within the torso, reciprocating bars connecting the crank arms in pairs, whereby the legs at each side of the toy will swing in unison, a substantially oblong frame pivotally supported by said bracket plate, ratchet wheel equipped 45 rollers journaled in the lower ends of said legs, pawl arms accommodated within said legs, said pawl arms having lower ends to engage the ratchet wheels and upper ends connected with the sides of said frame whereby when said frame is tilted laterally in one direction the pawl arms associated with the lowering side of said frame will engage their associated ratchet wheels while 5 the pawl arms at the rising side of said frame will move upwardly out of engagement with their ratchet wheels, and means operating in response to the reciprocatory movement of said bars for rocking said frame first in one direction 10 and then in a reverse direction.
3. In a quadrupedal toy, the combination of a torso and front and rear legs, a bracket plate mounted within said torso, pairs of shafts rockably supported on said plate, there being one 15 shaft for each leg, and each shaft having a leg-arm extending into a leg of the toy and a crank arm within the torso, reciprocating bars connecting the crank arms in pairs, whereby the legs at each side of the toy will swing in unison, 20 a substantially oblong frame pivotally supported by said bracket plate, ratchet wheel equipped rollers journaled in the lower ends of said legs, pawl arms accommodated within said legs, said pawl arms having lower ends to engage the 25 ratchet wheels and upper ends connected with the sides of said frame whereby when said frame is tilted laterally in one direction the pawl arms associated with the lowering side of said frame will engage their associated ratchet wheels while 30 the pawl arms at the rising side of said frame will move upwardly out of engagement with their ratchet wheels, and means operating in response to the reciprocatory movement of said bars for rocking said frame first in one direction 35 and then in a reverse direction, said means including a short shaft rotatably supported transversely of said bracket plate, means operatively connecting said shaft with one side of said frame for transmitting rocking movement of the shaft 40 to the frame to tilt the latter in either direction, and inter-engaging means on said shaft and on one of said bars for rocking the shaft in either of two directions incidental to the reciprocatory movement of said one of said bars. 45

CARL LARSEN.
